COLUMBIA PLANOGRAPH CO., WASHINGTON, D. C.

UNITED STATES PATENT OFFICE.

LYDA BECKER, OF INDIANAPOLIS, INDIANA.

FOLDING SKIRT-MARKER.

1,063,766.

Specification of Letters Patent.

Patented June 3, 1913.

Application filed June 25, 1912. Serial No. 705,791.

To all whom it may concern:

Be it known that I, LYDA BECKER, a citizen of the United States, residing at Indianapolis, in the county of Marion and State 5 of Indiana, have invented new and useful Improvements in Folding Skirt-Markers, of which the following is a specification.

This invention relates to skirt markers and the principal object of the invention is 10 to improve upon the structure shown in the patent granted to me March 12, 1912, #1,020,250, wherein the indicator is held in position upon the uprights 4 by means of set screws. In this type of device, each set 15 screw had to be loosened independently.

It is the object of this invention to avoid this difficulty, and broadly speaking, consists in providing means, whereby the indicator may be adjusted on all of the stand- 20 ards by a single operation.

A further object of the invention is to provide a simple and efficient device which may be cheaply constructed of light and yet durable structure, and which may be 25 readily operated to mark the length of the skirt being fitted so that it will hang evenly all around.

Further objects of this invention will appear as the following specific description is 30 read in connection with the accompanying drawing, which forms a part of this application, and in which:—

Figure 1 is a perspective view of the device. Fig. 2 is a side elevation. Fig. 3 35 is a similar view taken at right angles to Fig. 2. Fig. 4 is a detail top plan view. Fig. 5 is a detail vertical sectional view. Fig. 6 is a perspective view of a modified form.

Referring more particularly to the draw- 40 ing, 1 represents the base which may be formed of any suitable material, which may have any contour, or be made of any suitable size for the purpose for which it is intended. Mounted upon the base are keeper members 45 2 which are adapted to removably receive and retain the feet 3 of the standards 4. These standards 4 are provided with rack faces 5 and passed through apertures 6 formed in pairs in opposite sides of the in- 50 dicator ring 7. This ring may be con-

structed of any suitable size or of any suitable material having in mind only neatness of appearance, structural rigidity, and cheapness of production.

Mounted between the apertures 6 upon 55 the ring are suitable casings 8, each having a pair of sliding bolts or pawls 9 arranged therein and adapted to be projected in opposite directions by means of the spring pin which is interposed between the bolt. The 60 upper portion of the casing is slotted, as shown at 11, and passing through the slots are operating pins or handles 12 which are keyed to or otherwise secured to the bolts so that when the operating members are 65 drawn together, the bolts will be retracted from the rack face of the standards 4, thus permitting the indicating ring to be lowered. The upper ends of the bolts or pawls are 70 tapered off so that the ring may be moved upwardly without retracting the bolts by means of the operating members 12. If desired, the base and indicating ring may be constructed in the manner shown in my 75 patent and referred to, or they may consist of integral structures, as shown. Preferably, separate sets of standards are provided for supporting the indicating ring for ladies' or misses' dresses.

In the modification shown in Fig. 6, only 80 two standards are provided and carried by the indicator ring are casings in which the standards are adapted to slide. These casings 13 are provided so that the gravity of the free side of the indicator ring will not 85 affect its horizontal position. The casings 13 are provided with apertures to permit the passage of the pawls or bolts 10.

What is claimed is:—

1. In a skirt marker, a base, rack faced 90 standards extending vertically from the base, an indicator ring having apertures to receive said standards, and sliding bolts carried by the ring for engaging the rack faces of the standards to support the indicator ring in adjusted position thereon.

2. A skirt marker comprising a base, keeper members mounted thereon, rack faced standards having feet to removably engage said keeper members, an indicator 100

ring slidably mounted upon the standards, a casing carried by the indicator ring, bolts slidably mounted in the casing, and a spring for projecting said bolts in opposite directions into engagement with the rack faces of the standards.

In testimony whereof I affix my signature in presence of two witnesses.

LYDA BECKER.
